UNITED STATES PATENT OFFICE

2,103,555

DUST GUARD AND SEAL ASSEMBLY

Lawrence A. Rowe, Oak Park, Ill., assignor to
 MacLean-Fogg Lock Nut Company, Chicago,
 Ill., a corporation of Illinois

Application January 13, 1936, Serial No. 58,825

7 Claims. (Cl. 286—6)

The present invention relates to dust guard and seal assemblies, and is particularly concerned with improvements relating to the same type of dust guard assemblies for journal boxes of railway cars covered by my prior application, Serial No. 8, filed January 2, 1935, now Patent No. 2,070,865, granted February 16, 1937.

One of the objects of the present invention is the provision of an improved guard assembly which is not only adapted to exclude dust from the journal box of a railway car, but which is adapted to exclude water that might gain entrance to the box under ordinary conditions of service and care of the car, such as, for example, when the car is subjected to its usual washing.

The dust guard housing provided with an ordinary journal box usually has a relatively rough surface, the cavity in the housing being formed by a coring operation in the casting of the journal box, and one of the objects of the present invention is the provision of an improved guard assembly, including means for effecting a substantially water-tight seal between the rough inner surface of the dust guard assembly and the dust guard housing.

Another object of the invention is the provision of an improved guard per se which is adapted to effect a substantially water-tight joint between the rotating journal of the railway car wheels and the dust guard assembly so as to exclude water which might enter the journal box during a washing operation.

Another object of the invention is the improvement and modification of the floating dust guard assembly of the type covered by my prior application in such manner that all of the parts or layers of the assembly are adapted to be forced into resilient sliding contact with the adjacent layers or moving parts so that all of the parts of the assembly are adapted to exclude substantially all moisture or water which might otherwise enter between the various plates or layers of the assembly during a washing operation, or extreme weather conditions.

Another object of the invention is the provision of an improved guard assembly which is better adapted to exclude dust as well as water, and which, if desired, may be made into a substantially liquid-tight seal by suitable impregnation or grease packing of the parts of the guard assembly in the dust guard housing.

Another object of the invention is the provision of an improved water-tight dust guard assembly which is adapted to be used in the ordinary rough dust guard housing without any necessity for

machining any of the parts of the standard housings now in use on ordinary railway cars so that the present device may be successfully applied to existing railway cars without modification of either the device or existing car structure and with results that cannot be accomplished by any of the devices of the prior art.

Another object of the invention is the provision of a simple, sturdy, economical guard assembly and seal adapted to provide a better sealing connection between the rotating journal and the journal box of railway cars than the devices of the prior art.

Other objects and advantages of the invention will be apparent from the following description and the accompanying drawings, in which similar characters of reference indicate similar parts throughout the several views.

Referring to the drawings, of which there are two sheets,

Fig. 1 is a vertical sectional view, taken on the line passing through the axis of a railway car journal, showing the complete installation;

Fig. 2 is a front or outside elevational view of the guard assembly;

Fig. 3 is a fragmentary sectional view, taken on the plane of the line 3—3 of Fig. 2, showing the details of construction of the guard assembly cover;

Fig. 4 is a vertical sectional view, taken on the plane of the line which passes vertically through the dust guard housing and through the axis of the journal;

Fig. 5 is a view in perspective of the guard or seal per se;

Fig. 6 is a sectional view, taken on the plane of the line 6—6 of Fig. 5, looking in the direction of the arrows, the view being enlarged with respect to Fig. 5, and being substantially full size, with parts of the middle broken away;

Fig. 7 is a view in perspective of the housing sealing gasket per se, as seen from the right side of Fig. 4;

Fig. 8 is a fragmentary sectional view of a modified mode of attaching the felt or other compressible material of the gasket to its supporting plate;

Fig. 9 is a fragmentary sectional view, taken on the same plane as Fig. 4, through the lower part of a modification in which two gaskets are employed; and

Fig. 10 is a similar fragmentary sectional view, taken on the same plane, of the upper part of the same modification.

It has already been pointed out in detail in 55

my prior application, referred to above, that in the devices of the prior art the wooden dust guards which are disposed in the dust guard well or housing are apt to be crushed at the bottom when the journal box is jacked up and that the common wooden plug or wedge which was used for a closure of the dust guard well is apt to be kicked out of the dust guard well by movement of the guard.

10 The present guard assembly has all of the advantages of the floating dust guard structure of the application referred to, and has the additional advantage of providing a better seal for the space between the journal and journal box 15 so as to substantially exclude water when the car is washed.

10 The devices which will be described herein have been subjected to prolonged test by playing the water under pressure from a hose on the journal 20 between the wheel and journal box for a considerable length of time, without penetration of the water to the journal box. Of course, the assembly is also better adapted to exclude dust and other foreign matter from the journal box 25 by virtue of its more effective seal and the improved structure of all of the elements of the assembly throughout.

Referring to Fig. 1, 10 indicates in its entirety the dust guard assembly, which is disposed in 30 the conventional dust guard well 11. The conventional parts of the railway car are the journal box 12, journal 13, bearing 14, and wedge 15. The inner end of the journal box 12 is provided by a pair of walls 16, 17 which form the walls 35 of the dust guard well 11, and these walls are provided with enlarged apertures 18, 19, respectively, for passing the enlarged part 9 of the journal 13.

The guard 20 may be constructed of any suitable non-abrasive material, such as wood, bearing metals, cellulose by-products, wall boards, fabrics, leather, or the like; but I prefer to construct the dust guard body of a fiber board which may be manufactured of suitable masticated leather which is formed into a board.

Referring to Fig. 5, it will be noted that the guard per se 20 has a body which is substantially rectangular in form, but is provided with a cut-out portion at the corners 21, 22 and with the 50 circular end 23 which corresponds substantially to the shape of the dust guard well, but has its edges spaced from the walls of the dust guard well so as to permit a floating movement of the guard. Thus the guard 20 has a pair of vertical 55 straight side walls 24, 25, a flat top 26, and the circular bottom 23. It is provided with an aperture 24' that is substantially concentric with the curved boundary 23, and which is enlarged in the fiber board or other stiff body of the 60 guard with respect to the size of the journal part 9.

I prefer to construct the guard of a pair of pieces of the ply-board described, each piece having its enlarged aperture 27 and the two ply-board layers being provided with a flexible sealing member sandwiched between the ply-board layers and secured to the ply-board.

For example, the flexible sealing member 28 may consist of an annulus of oil tanned flexible 70 leather of suitable quality which is of sufficient width so that its outer edge extends well between the two layers 29—30 of fiber board and so that its inner edge has a diameter substantially less than the outer diameter of the journal part 9.

75 In some embodiments of the invention the flex-

ible leather seal 28 may be preformed with a cylindrical flange 31 for engaging the journal part 9 and with a radially extending flange 32 for securement between the fiber board members 29, 30 (Fig. 6).

Any suitable mode of securing these three members may be employed, such as cementing, riveting, stapling, or the like, and the securing members of metal or other material are preferably embedded in the surface of the fiber board so as not to interfere with the provision of a tight seal between the exterior surface of the fiber board and the plates which it slidably engages. I prefer to use the wire staples or clips 33, which are of substantially U shape, except that after the two legs have been passed through the fiber board 29, 30 and the leather flange 32, these legs are bent over toward each other on the opposite side of the guard.

The exterior outline of the dust guard 20 per se may take various shapes, but in order to accommodate the guard to provide space for the securing devices which hold the plates of the cover and dust guard assembly together, the guard is cut out at 21 and 22 to form the partially rectangular recesses shown, and provide suitable clearance between this guard and the securing devices so that the guard may have the floating action desired.

In some embodiments of the invention a seal which is sufficiently close may be secured by a close fit of the apertures 27 in the guard body about the journal part 9, or in some embodiments of the invention the present guard assembly might be utilized with the guard described in my prior application referred to. I prefer to utilize a guard with such a flexible leather seal which may be beveled at its cylindrical flange, if desired, to provide a relatively thin lip 34 engaging the journal part 9 and tending to be drawn into closer engagement with the journal by application of any pressure or force from the side toward which said lip extends.

Other flexible sealing materials which may be employed are impregnated fabrics, rubber, impregnated papers, felt, or the like, but leather is preferred on account of its capacity for long wear and its effective sealing action.

The present guard 20 is thinner than most of the devices of the prior art for the purpose of providing suitable space in the dust guard well for a gasket to seal the space between the guard assembly and the outer wall of the well and to provide space for the resilient members which compress this gasket and keep the parts of the assembly in tight sealing and sliding relation with respect to each other.

The guard 20, which may also be termed a seal, is slidably mounted between a pair of metal plates 35, 36. The plates 35, 36 are of substantially the same shape as the guard 20, but the apertures 37, 38 in these plates are larger with respect to the journal portion 9 than the aperture in the guard, since the guard is intended to seal and close the space between the floating plates 35, 36 and the journal part 9, and it is desired to keep the plates 35, 36 out of contact with the journal.

Thus the plates 35, 36 are each provided with the circular end portion 39, two straight sides 40, 41, and the straight upper end 42. These plates are preferably so arranged that they have a sliding or floating action with respect to a cover member 43, but the cover is preferably attached to the plates so that the cover cannot be removed.

without removing the plates. Furthermore, there is no possibility of the cover being completely forced from the top of the well by any action of the plates or removed in any way without first removing the journal from its position in the plate apertures 31, 38.

The plates 35, 36 are, therefore, provided with substantially rectangular grooves 44, 45 located in the straight side walls 40, 41 and surrounding the rivets 46, 47 and their spacers 48, 49. The walls of these rectangular grooves 44, 45 are spaced from the rivet spacers which are carried by the cover assembly 43, on all sides, so that these plates may move upward or downward or laterally with respect to the cover, the plates having such floating action as is imposed upon them by the engagement of the guard 20 with the stop members carried by the plates 38, 36.

20 The plates 35, 36 are preferably secured together at the top by a pair of rivets 50 and spacers 51, it being understood that the spacers 51 are tubular members surrounding the rivets and spacing plates 35, 36, and the rivets extend through both plates and spacers and clamp the plates against the ends of the spacers. In a similar way additional securing may be provided for the plates 35, 36 by further rivets and spacers 52, 53 located adjacent the upper end of the plates 35, 36, but slightly spaced therefrom and located in the cut-out portions 25 21, 22 of a guard 20.

25 The rivets and spacers 52, 53 also act as stop members for engaging the edges 54 of the guard and preventing rotation of the guard on the journal. These particular rivets and spacers also act as stops and permit the guard 20 to cause floating action of the plates 35, 36 with respect to the cover assembly 43, this action of the 30 plates being limited by the clearance which is provided between the rivets and spacers 46-49 and the grooves 44, 45.

35 In the guard assemblies described in my prior application, additional securing devices were preferably provided between the plates 35, 36 at the sides and bottom of these plates, thereby holding the plates in engagement with the sides of the guard by the action of these securing devices. In the present embodiment I prefer to 40 dispense with further securing devices between the plates 35, 36 below the rivets 52 so that these plates have a free spring action at all points around the guard 20 and so that the plates may be resiliently forced into tight sliding engagement with the guard 20, even after the guard has 45 shown some wear.

45 The guard assembly is preferably provided with resilient means for urging the assembly into sealing contact with one of the walls of the dust 50 guard well, such as, for example, the wall 17. In order to accomplish this result the cover assembly 43 (Fig. 3) is preferably provided with a pair of resilient steel members 55, which comprise strips of metal that are secured to the outer plates 56 of the cover assembly by rivets 57 at the top. The spring fingers 55 are bowed out at the middle and may have their lower ends 58 engage the plate 56 also, the lower ends 58 being bent out parallel to the plate 56.

50 The resilient members 55 are adapted to engage the inside of the dust guard wall 16, flexing sufficiently to permit the assembly to be forced into the well, but forcing all of the parts of the dust guard assembly over against the right wall 55 17 of Fig. 1 to effect a sealing contact between

all of the parts of the assembly and with that wall.

The floating plate 36 may also be provided with spring fingers 59 located near the lower end of the plate 36 on the same side as the spring fingers 55. The resilient members 59 are also made of spring steel and secured by a pair of rivets 60 to the plate 36. These resilient members 59 may be made of substantially T shape, the members being bowed out again at the middle, and having 10 the end slidably engaging the plate 36, as in the case of the resilient members 55.

15 It will be noted that the spring fingers 55 are relatively wide and have more surface engagement with the wall 16 of the dust well 11 for the purpose of holding the cover assembly 43 quite securely in the well. The spring fingers 59 are narrower and preferably not so stiff, so that they permit sliding movement of the plates 36 in the dust guard while they still urge the dust guard 20 toward the right in Fig. 1.

20 The cover assembly 43 preferably comprises a cover plate 61, which may be of rectangular shape and of sufficient size to close the upper end of the dust guard well overlying both of the walls 25 16 and providing sufficient body on the cover plate to secure a lining of gasket material 62.

25 The gasket or lining 62 may consist of a strip of felt, rubber, sponge rubber, or any other suitable gasket material or fabric suitably impregnated, but ordinary felt has been found to accomplish the desired result economically and effectively. This layer of felt 62 is preferably secured to the under side of the cover plate 61 surrounding a pair of vertical plates 56, 63, by means 30 of a plurality of rivets 64.

35 The rivets 64 preferably pass through a metal strip 65 as well as the felt 62 and cover plate 61, so that the metal strips 65 may serve to compress and secure the felt to the cover plate 61, greatly 40 increasing the area of engagement of the securing devices. The metal plate 65 is preferably disposed in such manner that the exposed felt 62 will come into engagement with the upper edges of the dust guard well walls 16, 17 rather than 45 the metal plate 65, the felt effectively sealing this juncture against dust and the application of water as it is used in the cleaning of the car. When the cover assembly is applied to the dust guard well, it is pressed down into the well and 50 held in place by the spring fingers 55, which engage the wall 16 of the well.

55 As previously stated, the floating plates 35, 36 are preferably permanently attached to the cover assembly 43, and for this purpose the cover plate 55 61 carries the depending parallel supporting plates 56, 63. These plates are provided (Fig. 4) with laterally projecting attachment flanges 66 which may be riveted, welded, or otherwise 60 permanently secured to the cover plate 61.

65 The flanges 66 preferably extend outward under the felt gasket 62, and the plates 55, 63 are supported on the cover in position to slidably engage the floating plates 35, 36.

70 The shape of the plates 56, 63 is shown in Fig. 65 2, each plate having a straight upper edge, straight side edges 67, and a flat lower edge 68 between two depending legs 69. Each leg 69 is provided with rivets and spacers 46-49, by means of which the legs of the two plates are secured 70 together in spaced relation at each side of the cover assembly. Rivets and spacers 46-49 also serve as stops, as previously described, to limit the movement of the sliding plates 35, 36, with respect to the cover assembly 43, by virtue of the 75

engagement of these rivets with the walls of the grooves 44, 45.

In order to provide a water-tight seal between the guard assembly and the relatively rough inner surface of the wall 17 of the dust guard well 11, I prefer to provide a gasket 70 between the plate 35 and the wall 17, the gasket being shown in perspective in Fig. 7.

The gasket 70 preferably comprises a metallic supporting body 71, which may be used to permit sliding engagement between the gasket and the guard assembly during the insertion of the guard, and the metallic supporting body may carry a layer of compressible gasket material 72, such as rubber, impregnated fabric, or any suitable material, but I prefer ordinary felt, which may be impregnated with suitable oils, grease, or other materials, if desired.

The supporting plate of the gasket may likewise be made of hard rubber, fiber board, wood and various stiff non-abrasive materials.

The gasket 70 may have substantially the same external shape in elevation as the guard 20, as will be seen from a comparison of Figs. 5 and 7. It has, however, been provided with a larger oblong opening 13, which corresponds substantially to the size and shape of the openings 18 and 19 in the dust guard well walls 16 and 17.

Various external shapes of gaskets may be used, the principal idea being to provide a seal completely about the opening 19 in the wall 17 of the dust guard well.

The felt 72 may be secured to the metal backing 71 in the same manner as the felt is secured to the cover plate 61; that is, by a plurality of rivets 74 passing through the felt, the plate 71 and a metal washer plate 75, which may also extend completely around the opening 13, but is spaced therefrom.

I prefer to secure the felt by forming a hairpin bend in each edge of the metal supporting plate 71, thereby providing the plate with a securing flange 76 at each edge, which compresses and clamps the felt at a point adjacent each edge. At its central portion the felt backing bulges or swells outward and is adapted to engage the inner surface of the wall 17, and the felt is so compressed at the flanges 76 that these flanges do not come in contact with the metal 50 of the dust guard well, the entire contact being between the felt and the wall 17. The thickness of the felt is such that it is compressed considerably when the guard assembly is inserted in the well; and the felt being under a condition of 55 compact compression, it assumes a substantially impervious condition and conforms itself to the rough inner surface of the wall 17 so as to provide a water-tight seal between the gasket and this wall. In some embodiments of the invention plastic or sponge rubber or any other kind of resilient rubber or rubber impregnated fabric may be vulcanized, cemented or otherwise secured to a metal plate to form a gasket.

The outer side of the metal supporting plate 71 is provided with a flat surface which is adapted to engage the flat surfaces of the adjacent metal plate 36, thereby providing a substantially liquid-tight joint at this point. Of course, if desired, the joints may be further improved and sealed 70 by the use of a film of oil or grease on the contacting parts.

It should be noted that the upper end of the gasket 70 substantially clears the lower edge 68 of the adjacent plate 42 which depends from the 75 cover plate 43, so that the sealing contact is en-

tirely between the plate 36 and the gasket plate 71, and the gasket does not interfere with the cover or its depending plates.

The method of assembly of the parts with the dust guard well is as follows: The assembly must, of course, be placed in the well prior to the placing of the journal box on the journal 13. The gasket 70 is first inserted in the well with its felt surface engaging the inner side of the wall 17. The dust guard or seal assembly, which may be lifted by means of the cover plate 61, is then inserted into the dust guard well, the outer surface of the plate 36 sliding against the surface of the gasket plate 71, which prevents the felt from being torn during this operation of insertion. As the guard assembly is forced down into the well, the spring fingers 59 and 55 are compressed, and the felt 72 is compressed, and the resilient plates 35, 36 are forced into close engagement with the sides of the guard 20.

When the cover plate 61 has been forced well down upon the top of the dust guard well, the parts are in proper position and the cover is held in place by the spring fingers 55, which frictionally engage the walls of the well.

The cylindrical flange 31 on the leather sealing member of the guard 20 preferably extends away from the journal box 12, that is, toward the wheel, and in order to permit the insertion of the journal 13 a suitable spreader is placed 30 inside of this cylindrical flange 31, while the journal is inserted, after which the spreader is removed and the resilient leather flange 31 comes into engagement with the cylindrical part 9 of the car journal.

Referring to Figs. 9 and 10, these fragmentary sectional views show a modification in which the resilient means for holding the parts of the assembly in close sliding contact may be another gasket similar to the gasket 70. In this embodiment another gasket 80 is inserted on the opposite side of the dust guard well, and the depending flange 81 on the cover plate is formed like the flange 63 on the opposite side; that is, it is made sufficiently shorter so that it clears 45 the gaskets instead of being as long as the flange 56 of Fig. 3. Of course, the spring fingers 59 must be wholly eliminated so that the flat metal backing of the gasket 80 can engage the plate 36, and the spring fingers 55 on the cover plate 50 may be either eliminated or placed far enough to one side adjacent the ends of the cover so as to eliminate any interference between these spring fingers and the gaskets 70 and 80. The use of two gaskets makes a still more nearly perfect seal between the walls of the dust guard well of the assembly.

It will thus be observed that I have invented an improved guard assembly which provides a substantially water-tight seal between the journal and the opening in the journal box surrounding the journal.

While I have illustrated a preferred embodiment of my invention, many modifications may be made without departing from the spirit of 65 the invention, and I do not wish to be limited to the precise details of construction set forth, but desire to avail myself of all changes within the scope of the appended claims.

Having thus described my invention, what I 70 claim as new and desire to secure by Letters Patent of the United States, is:

1. In a dust guard assembly, the combination of a dust guard comprising a pair of relatively thin sheets having an enlarged aperture for pass- 75

- ing a railway car journal, said sheets having a sealing member of flexible material secured between them, said sealing member being formed with a centrally located aperture bordered by a 5 cylindrical flange engaging a cylindrical portion of a railway car journal, a shiftable housing comprising a pair of metallic sheet metal plates having enlarged apertures, the apertures being smaller than the outer area of said dust guard whereby the dust guard may shift between said metallic sheets to adapt itself to the position of the railway car journal, a gasket of yieldable material engaging the inner wall of a dust guard well and having a metallic backing slidably 10 gaging one of said sheets, and means for urging said assembly toward one side of the dust guard well to place a compression upon said yieldable gasket and to effect a water-tight seal between the railway car journal and the dust guard well.
2. In a dust guard assembly, the combination of a dust guard comprising a pair of relatively thin sheets having an enlarged aperture for passing a railway car journal, said sheets having a sealing member of flexible material secured between them, said sealing member being formed with a centrally located aperture bordered by a cylindrical flange engaging a cylindrical portion of a railway car journal, a shiftable housing comprising a pair of metallic sheet metal plates having 15 enlarged apertures, the apertures being smaller than the outer area of said dust guard whereby the dust guard may shift between said metallic sheets to adapt itself to the position of the railway car journal, a gasket of yieldable material 20 engaging the inner wall of a dust guard well and having a metallic backing slidably engaging one of said sheets, and means for urging said assembly toward one side of the dust guard well to place a compression upon said yieldable gasket and to effect a water-tight seal between the railway car journal and the dust guard well, said dust guard assembly also comprising a cover member having depending metallic flanges movably mounted on said metal sheets whereby the 25 cover is secured against being knocked out of closing relation to said dust guard well.
3. In a guard assembly for railway car journal boxes, the combination of a guard having a liquid-tight sealing connection with a cylindrical part of a railway car journal, a pair of resilient metal plates slidably engaging said guard and closing the space between said guard and the edges of the apertures for the railway car journal in the journal box, and a compressible gasket forced into engagement with the rough inner 30 wall of the guard well and providing a sealing engagement between said wall and one of said resilient metal plates, said gasket also comprising a supporting metal backing adapted to maintain the shape of the gasket and to permit sliding engagement between one of said resilient metal plates and the gasket during the insertion of the 35
- guard assembly, said resilient means comprising a plurality of fingers for engaging the wall of the well which is opposite to the wall engaged by said gasket.
4. In a guard assembly for railway car journal boxes, the combination of a guard having a liquid-tight sealing connection with a cylindrical part of a railway car journal, a pair of resilient metal plates slidably engaging said guard and closing the space between said guard and the 40 edges of the apertures for the railway car journal in the journal box, and a compressible gasket forced into engagement with the rough inner wall of the guard well and providing a sealing engagement between said wall and one of said resilient metal plates, said assembly comprising a cover having a pair of depending plates movably secured with respect to said resilient plates, and said cover having a sealing gasket material carried by its under side for engaging the top edges 45 of the dust guard well.
5. In a dust guard assembly, the combination of a supporting cover with a pair of depending spaced plates carried by the under side of said cover, said plates being provided with a pair of stop rivets, one located adjacent each lateral edge, and a guard housing comprising a pair of spaced resilient metal plates adapted to be received between the depending plates and having stop shoulders formed about said stop rivets, said 50 guard housing plates being secured together in spaced relation by suitable securing means located adjacent their upper edges.
6. In a dust guard assembly, the combination of a supporting cover with a pair of depending spaced plates carried by the under side of said cover, said plates being provided with a pair of stop rivets, one located adjacent each lateral edge, a guard housing comprising a pair of spaced resilient metal plates adapted to be received between the depending plates and having stop shoulders formed about said stop rivets, said guard housing plates being secured together in spaced relation by suitable securing means located adjacent their upper edges, and a guard 55 comprising a suitable supporting body of substantially rigid material having an aperture for passing a car journal with a clearance and a flexible sealing member bordering said aperture and adapted to engage a rotating part of said journal.
7. In a dust guard assembly, the combination of a pair of supporting plates, each plate being adapted to be received in a dust guard well, and each plate having a resilient sealing material on its outer side, and a dust guard slidably mounted between said plates and having an aperture for receiving a portion of the car wheel journal, said sealing material comprising sponge rubber vulcanized to said supporting plate.

LAWRENCE A. ROWE.
